VAPORIZING TANK

Russell Frank Goode, Flint Hill, Va., assignor of
one-half to Jacob Edward Keyser, Washington,
Va.

Application July 19, 1943, Serial No. 495,347

7 Claims. (Cl. 261—36)

This application is a continuation-in-part of my prior application on Vaporizing tanks, Ser. No. 414,003, filed October 7, 1941.

This invention relates to an improvement in vaporizing tanks, of the character used for vaporizing hydrocarbon fuel used in internal combustion engines.

Fuel feeding devices have been employed heretofore for supplying fuel to internal combustion engines, but frequently fail to vaporize completely the fuel supplied to the engine, resulting in the admission of liquified fuel thereto which fails to ignite and thus is wasted.

The object of this invention is to obtain more perfect and complete vaporization of the fuel, whereby it is supplied in a form readily and completely combustible, eliminating waste, and obtaining more efficient operation of the engine, substantially with Diesel engine performance. At the same time, provision is made for complete safety in the event that the motor vehicle in which the tank is used should turn over, by closing openings to confine the fuel in the tank against accidental leakage or flow therefrom.

Provision is made for confining a quantity of fuel in a tank and for warming and vaporizing the fuel therein in the path of air flow through the tank over the fuel, which air flow is caused by the suction created by the engine in the intake manifold with which the tank is connected. Suitable valves are provided for controlling the air admission and discharge from the tank, and provision is made for closing the air inlet valve in the event that the vehicle turns over or becomes upset from its normal upright position.

Provision is made for heating the body of fuel in the tank, and for withdrawing the heated liquid fuel and discharging the same in the air adjacent the top of the tank substantially in the form of a jet, which will facilitate the ready vaporization of the liquid fuel as the air is drawn through the top portion of the tank, being fed to the intake manifold of the engine in the form of a vapor that is readily and completely combustible. Provision is made for controlling the air supply through the top of the tank, as well as controlling the feeding of the fuel therein, automatically in accordance with the speed of the engine, thereby supplying the proper and required amount of fuel to the engine. When the engine is to be started initially a rich mixture of fuel may be atomized into the air stream at a point at or adjacent the intake manifold for starting purposes, under control of a choke automatically operated in the usual way, after which the rich

feeding is discontinued and the device shifted back to the feeding of vaporized fuel from the top of the tank, as described.

A preferred embodiment of the invention is illustrated in the accompanying drawings, in which:

Fig. 1 is a longitudinal sectional view through the vaporizing tank;

Fig. 2 is a longitudinal vertical section through the feed control valve;

Fig. 3 is a horizontal sectional view through the tank on the line 3—3 of Fig. 1;

Fig. 4 is a diagrammatic view showing the assembly of the tank with the engine;

Fig. 5 is a vertical cross section through the tank on the line 5—5 of Fig. 1;

Fig. 6 is a detail vertical section through the air intake valve control; and

Fig. 7 is a cross section thereof taken on the line 7—7 of Fig. 6.

The fuel vaporizing tank is designated generally by the numeral 1 and is shown as having a closed top formed by a cover 2 which is fitted thereover and sealed to the side walls of the tank 25 as by bolts. The tank 1 is adapted to be filled partially full of liquified fuel, having a filling tube 3 (Figs. 3 and 5) extending into the tank 1, with a filling cap 4 detachably mounted on the tube 3 in the usual manner. A vent tube 5 extends along the inside and outside of the filling tube 3 from a point adjacent within the top of the tank to a point near the external upper end of the tube 3 to establish air communication therewith in admitting air to and discharging the 35 same from the top of the tank.

The tank 1 may be enclosed, if desired, within a sheath of heat insulating material, such as asbestos, or the like, that will protect the fuel within the tank from excess vaporizing action, except 40 when required, especially when the tank is located in close proximity with the engine. The top of the tank preferably has a pressure release valve 6 connected therewith for releasing excess pressure therefrom to the exhaust line of the engine.

One end of the tank 1, at the cover 2, is provided with an air inlet 7, which may be connected with a pipe 8, if desired, extending to a point adjacent the warm air hose of the engine or other source of warm air for the purpose of 50 admitting warmed air into the upper portion of the tank.

The air inlet 7 is adapted to be controlled by a valve 9 having an enlargement 10 on the outer side thereof in position to be engaged by a cam 55 11 carried by a butterfly valve 12 which is piv-

totally supported eccentrically thereof on a shaft 13 adapted to be actuated by the usual choke connection indicated generally at 14.

The valve 9 is slidably mounted upon and supported by a guide rod 15 secured to brackets 16 depending from the top 2 of the tank, and to which brackets the rod is rigidly secured, being held against endwise displacement relative thereto.

The valve 9 is urged toward its closed position by a coiled spring 17 surrounding the stem of the valve and the telescoped end of the rod 15, being interposed between the disc of the valve 9 and a cam disc 18. The cam disc 18 is fixed against rotary movement relative to the guide rod 15 by a pin 19 extending therefrom through a slot in the guide rod. A hump 20 on the cam disc 18 is arranged to engage in a notch 21 formed in the face of a cam 22 rotatably supported on the guide rod 15 between the disc 18 and the adjacent supporting bracket 16. The cam 22 carries a depending arm 23 having a weight 24 at the lower end thereof normally tending to hold the cam 22 in its central position, as shown in Figs. 6 and 7.

In the event that the vehicle should become upset or should turn over, the shifting of the weight 24 would cause rotation of the cam 22, immediately applying endwise pressure to the spring 17, increasing the tension thereof sufficiently to close the valve 9 tightly against its seat, the spring thereby overcoming the suction on the valve disc which normally opens it. This closing of the valve thereby seals the inlet of the tank and confines the liquid fuel therein, thus tending to avoid the danger of fire that often results from the upsetting of a vehicle.

The valve 9 is opened normally by a suction device, as hereinafter described, the force thereof being sufficient to overcome the tension applied by the spring 17 to the disc of the valve 9, thereby opening the valve to admit air into the vaporizing chamber of the tank. To limit this opening movement, an auxiliary spring 25 is sleeved around the end of the guide rod 15, bearing at one end against a stop pin 26, but spaced at the opposite end from the valve stem when the valve is closed. Upon opening movement of the valve 9, the stem thereof engages the spring 25 which thereby limits this opening movement.

Provision may be made, if desired, for holding the cam 22 in a lateral position to which it has been shifted upon upsetting of the vehicle, thereby to maintain the valve 9 closed until the vehicle has been restored to full operative condition. For this purpose, I have provided recesses 27 in the face of the cam 22, on opposite sides of the center thereof, as shown in Fig. 7, in position to be engaged by a pin 28 slidably mounted in the adjacent bracket 16. An adjustable spring 29 bears against the pin 28 tending to press the same into the recess 27 upon swinging movement of the weight 24 to either lateral position. This release may be accomplished in any desired manner as, for instance, by inserting an implement through a normally closed orifice in the top 2 of the tank. It will be evident that upon release of the pin 28, the cam 22 will be moved to its normal central position by the weight 24, thus allowing operation of the valve 9 in the usual manner.

At the opposite side of the tank 1 is provided a discharge port 30 connected with and surrounded by an enlarged cap 31. A conduit 32 extends from the cap 31 to a connection 33 attached to the

intake manifold 34 of an engine 35 and forms a fuel inlet pipe for the engine.

The discharge port 30 has a valve seat 36 therein in a position to be engaged by the valve 37 having a stem slidably mounted on the guide rod 15. The valve 37 is adapted to be opened by the suction of the engine. The valve 37 is normally maintained closed when the engine is not running, by a coiled spring 39 interposed between a disc 40 fixed by a pin 41, and a disc 42 fixed to the stem of the valve 37, permitting limited sliding movement of the valve 37.

A combined valve and atomizing unit is mounted in the top of the tank 1, preferably above the liquid lever therein, as shown in Figs. 1 and 2. The unit is constructed of a body 43 having a longitudinal passage 44 therethrough, communicating at one end with a liquid discharge nozzle or jet 45, and at the opposite end, with a connection for a discharge tube 46 (Fig. 3). The passageway 44 intermediate its ends, is connected through a tube 47 extending to the conventional fuel pump 48, the opposite side of which is connected with an eduction tube 49 which extends downwardly in the tank 1 to a point adjacent the bottom thereof. The pump 48 is operated in the usual manner, by the operation of the engine, being ordinarily a vacuum pump operated by the cam shaft of the engine. It will be evident that the operation of the pump 48 will withdraw liquid fuel from a point adjacent the bottom of the tank 1 and discharge the same under pressure through the passageway 44, either to the discharge jet 45 or to the discharge tube 46.

The fuel discharge is controlled by a sliding valve member 50 having orifices 51 and 52 therein in positions to register alternately with the opposite ends of the passageway 44, the opening 51 permitting discharge from the passageway to the jet 45, while the opening 52 permits discharge to the tube 46 when the valve member 50 is shifted to its opposite position from that shown in Fig. 2. The valve member 50 is connected with one end of a lever 53 pivotally supported intermediate its ends at 54 on the guide rod 15. The opposite end of the lever 53 is connected with the diaphragm of a vacuum unit 55 suitably mounted within the tank 1, as for instance on the filling tube 3, as shown. The vacuum unit 55 is connected through a tube 56 with the intake manifold to be actuated in response to the creation of suction therein by the operation of the engine. A spring 57 may be connected with the lever 53 to restore said lever and its connected parts to their normal positions after the operation of the engine has stopped. The connections with the lever 53 are through slots that permit swinging movement of the lever without binding said connections. The lever 53 is connected also through a link 65 with the valve 9 to open said valve upon actuation of the vacuum unit 55.

The supply tube 46 extends out of the tank 1, through the cap 31 and conduit 32 so as to direct the liquid fuel to a point adjacent the intake manifold 34. The tube 46 terminates in a check-valve unit 58 located in the chamber 33. The check valve in the unit 58 is arranged to close against back pressure through the tube 46, although allowing discharge of the liquid fuel therefrom. A check-valve 59, may be provided to connect the chamber 33 with the intake manifold 34. The intake manifold is provided also with the usual butterfly throttle valve 60 to control the feeding of the fuel to the engine.

Provision is made for heating the fuel in the bottom portion of the tank 1, for which purpose I have shown a hot air heater at 61 connected through pipes 62 and 63 with a source of hot air, such for instance as the exhaust manifold of the engine. A thermostatic valve 64 should be provided in the intake pipe 62, as shown, to regulate the supply of hot air to the heater 61, and thereby regulate the temperature of the fuel in the tank.

In operation, the vaporizer is designed to supply fuel in vapor form to the intake manifold of the engine and in such condition that all of the fuel will be consumed through normal operation. However, when the engine is to be started, it usually requires the supply of a richer mixture thereto than for normal operation. For this purpose, I have provided the choke 14 which substantially closes the air control valve 12 in the air inlet 1, and acts through the cam 11 bearing against the projection 10 on the valve 9, to move the valve inwardly thus moving the link 65 which connects the valve with one end of the lever 53. This movement will slide the valve member 50 to the right in Figs. 2 and 3, thus moving the orifice 52 into registry with the adjacent end of the passageway 44. The lever 53 is permitted to swing far enough to open the orifice 52 without having its movement limited by the vacuum unit 55 because of the lost-motion by the slot in said lever, where the unit is connected therewith. Then, the operation of the fuel pump 48 will cause fuel to be withdrawn from the bottom of the tank and directed through the tube 47, passageway 44, orifice 52, and tube 46, through which it is discharged at the valve unit 58 into the intake manifold 34 for combustion in the engine. Very little air will be drawn through the top of the tank during this spraying operation, due to the partial closing of the valve 12, but just sufficient air will be admitted to the manifold to support combustion of the relatively rich mixture in the cylinders of the engine.

After the starting of the engine, the choke 14 may be shifted to its normal position, thus opening the valve 12 as shown in Fig. 1. The engine suction, when the engine is started, will act on the vacuum unit 55, but the spring 51 will shift the valve member 50 to move the orifice 52 out of registry with the passageway 44, although the vacuum unit 55 will act to hold the orifice 51 in registry with the passageway 44, but the limited motion of the unit 55 will not cause movement of the valve 50 far enough to open the valve orifice 52. This will cause the liquid fuel to be discharged from the passageway 44 in through the jet or spray 45 in the path of movement of air through the top of the tank. Since the liquid fuel is maintained in a warm condition by the heater 61, the spraying of this liquid fuel in the air stream will aid the material vaporization thereof by the heat to insure a full supply of vaporized fuel.

I have found from actual experience by the operation of this unit, that it is far more efficient than the normal or conventional carburetor units, producing more nearly Diesel efficiency.

If the tank 1 be constructed of substantial size, it may be equipped with a perforated baffle 66 therein to prevent splashing of the fuel and undue vaporization, especially when riding over rough roads. Additional baffles are shown at 67 and 67' adjacent the air inlet port 1 and the discharge passage 30, to prevent the splashing of fuel out through said ports. The baffle 67' is preferably just above the lower end of the jet tube

45, and prevents direct suction of the fuel from the jet to the passage 30 without adequate vaporization.

I claim:

1. A fuel vaporizer comprising a tank adapted to contain liquid fuel with an air space thereabove, said tank having an inlet and outlet at different sides thereof in communication with said air space, a guide rod mounted in the tank and extending between the inlet and outlet, valves slidably mounted on said guide rod in position to control respectively the inlet and outlet, resilient means acting on the respective valves tending to hold the same closed, cam means acting on the resilient means of one valve for varying the tension thereof, said cam means being journaled on the guide rod, a weight supported by the cam means and suspended in the tank in position for turning the same upon upsetting of the tank, linkage connected with the last-mentioned valve for opening movement thereof, and actuating means for said valve connected with the linkage.

2. A fuel vaporizer comprising a tank adapted to contain a liquid fuel with a vapor space thereabove, said tank having a mixture outlet at a side thereof in communication with said vapor space and having an air inlet at a side thereof into said vapor space, a discharge jet mounted in the vapor space in the tank, a second jet in the mixture outlet externally of the tank, means for supplying fuel to said jets, valve means for controlling the supply of fuel to the respective jets from said fuel supplying means, a valve for controlling the air-inlet, and control means operatively connected with the fuel supply valve means for causing fuel to be directed only to the first-mentioned jet when the inlet valve is open and for discontinuing direction of fuel to said first-mentioned jet and causing fuel to be directed only to the second-mentioned jet when the inlet valve is substantially closed.

3. A fuel vaporizer comprising a tank adapted to contain a liquid fuel with a vapor space thereabove, said tank having a mixture outlet at a side thereof in communication with said vapor space and having an air inlet at a side thereof into said vapor space, a discharge jet mounted in the vapor space in the tank, a second jet in the mixture outlet externally of the tank, means for supplying fuel to said jets, valve means for controlling the supply of fuel to the respective jets from said fuel supplying means, a valve for controlling the air-inlet, and control means operatively connected with the inlet valve and fuel supply valve means for causing opening movement of the air inlet valve upon movement of the fuel valve means for causing fuel to be directed only to the first-mentioned jet when the inlet valve is open and to cause fuel to be directed only to the second-mentioned jet when the inlet valve is substantially closed.

4. A fuel vaporizer comprising a tank adapted to contain a liquid fuel with a vapor space thereabove, said tank having a mixture outlet at a side thereof in communication with said vapor space and having an air inlet at a different side thereof into said vapor space, an engine inlet pipe connected with the outlet and leading therefrom, a discharge jet mounted in the vapor space in the tank at a point remote from the outlet, a second jet in the engine inlet pipe externally of the tank, means for supplying fuel to said jets, valve means for controlling the supply of fuel to the respective jets from said fuel supplying means, a valve for controlling the air inlet, linkage means connect-

ing said inlet valve with the valve means for causing opening movement of the inlet valve when the valve means is moved to supply fuel to the first-mentioned jet and for closing movement of the inlet valve upon movement of the valve means to supply fuel to the second jet, and means for moving said inlet valve and valve means.

5. A fuel vaporizer comprising a tank adapted to contain a liquid fuel with a vapor space thereabove, said tank having a mixture outlet at a side thereof in communication with said vapor space and having an air inlet at a different side thereof into said vapor space, an engine inlet pipe connected with the outlet and leading therefrom, a discharge jet mounted in the vapor space in the tank at a point remove from the outlet, a second jet in the engine inlet pipe externally of the tank, means for withdrawing liquid fuel from within the tank and for directing said liquid fuel under pressure to the respective jets, valve means for controlling the supply of fuel to the respective jets, a valve for controlling the air inlet, linkage means connecting said inlet valve with the valve means for causing opening movement of the inlet valve upon movement of the valve means to supply fuel to the first-mentioned jet and for causing closing movement of the inlet valve upon movement of the valve means to supply fuel to the second jet, and power means for causing said coordinated movements of the inlet valve and valve means.

6. A fuel vaporizer comprising a tank adapted to contain a liquid fuel with a vapor space thereabove, said tank having a mixture outlet at a side thereof in communication with said vapor space and having an air inlet at a different side thereof into said vapor space, an engine inlet pipe connected with the outlet and leading therefrom, a discharge jet mounted in the vapor space in the tank at a point remote from the outlet, a second jet in the engine inlet pipe externally of the tank, means for withdrawing liquid fuel

from within the tank and for directing said liquid fuel under pressure to the respective jets, valve means for controlling the supply of fuel to the respective jets, a valve for controlling the air inlet, linkage means connecting said inlet valve with the valve means for causing opening movement of the inlet valve upon movement of the valve means to supply fuel to the first-mentioned jet and for causing closing movement of the inlet valve upon movement of the valve means to supply fuel to the second jet, power means for causing said coordinated movements of the inlet valve and valve means, and a valve for closing the mixture outlet and constructed for opening movement automatically in response to engine suction action.

7. A fuel vaporizer comprising a tank, said tank including a bottom section forming a sump and a top section forming a cover, said sections cooperating to enclose a chamber in the tank, valve mechanism enclosed within the chamber and having a fuel discharge jet connected therewith and mounted in the chamber, said valve mechanism and jet being mounted on the top section and carried thereby, said tank having a mixture discharge opening at one side thereof and having an air inlet at a side thereof, a fuel eduction tube connected with the top section and extending through a side thereof and downwardly into the sump, a fuel inlet tube extending through a side of the top section to the valve mechanism, and pump means externally of the tank connected with said tubes for withdrawing liquid fuel through the eduction tube and discharging said liquid fuel through the inlet tube and the valve mechanism to the jet, said tank top section being detachably connected with the bottom section for removal therefrom for assembly and adjustment of the valve mechanism and jet carried thereby.

40 RUSSELL FRANK GOODE.
